LLP

(57) **CLAIM**

We claim the ornamental design for a right angle drill, as
shown and described.

DESCRIPTION

FIG. 1 is a front perspective view of a right angle drill in
accordance with an embodiment of the invention.

FIG. 2 is a left side view of the right angle drill of FIG. 1.

FIG. 3 is a right side view of the right angle drill of FIG. 1.

FIG. 4 is a top view of the right angle drill of FIG. 1.

FIG. 5 is a bottom view of the right angle drill of FIG. 1.

FIG. 6 is a front view of the right angle drill of FIG. 1; and,

FIG. 7 is a rear view of the right angle drill of FIG. 1.

The portions of the right angle drill shown in broken lines are
included for the purpose of illustrating environment and form
no part of the claimed design.

1 Claim, 5 Drawing Sheets
